[57] CLAIM

The ornamental design for a combined bottle cap and pill divider, as shown and described.

DESCRIPTION

FIG. 1 is a perspective view of a combined bottle cap and pill divider, showing our new design;

FIG. 2 is another perspective view with the article partially rotated;

FIG. 3 is an elevational view on a reduced scale;

FIG. 4 is a view looking from the left of FIG. 3;

FIG. 5 is a top plan view thereof; and,

FIG. 6 is a bottom plan view thereof.
